CABINET PULL OR SIMILAR ARTICLE

Dean W. Myers, Newport Beach, Calif., assignor to Jaybee Manufacturing Corp., Los Angeles, Calif., a corporation of California

Original design application May 20, 1963, Ser. No. 74,966, now Design Patent No. 197,700, dated Mar. 17, 1964. Divided and this application Dec. 26, 1963, Ser. No. 78,464

Term of patent 14 years

(Cl. D10—8)

FIGURE 1 is a front elevational view of a cabinet pull or similar article incorporating my new design;

FIG. 2 is a side elevational view thereof;

FIG. 3 is a sectional view taken along the plane corresponding to line 3—3 of FIG. 1; and

FIG. 4 is a front elevational view of a modified form of the cabinet pull shown in FIG. 1, differing therefrom in the reversal of the contrasting areas.

The characteristic feature of my design for a cabinet pull or similar article resides in the configuration and arrangement of the specific decorative details indented on the front surface thereof. The stippled shading indicates contrasting areas.

This is a division of application Serial Number D. 74,966 filed May 20, 1963, now Patent Number D. 197,700, granted March 17, 1964.

I claim:

The ornamental design for a cabinet pull or similar article, substantially as shown and described.
